UNITED STATES PATENT OFFICE.

JOHN C. FEICKERT, OF SAN FRANCISCO, CALIFORNIA.

WHIP-SOCKET.

No. 928,870.

Specification of Letters Patent. Patented July 20, 1909.

Application filed October 31, 1908. Serial No. 460,485.

To all whom it may concern:

Be it known that I, JOHN C. FEICKERT, a citizen of the United States, residing at San Francisco, in the county of San Francisco, State of California, have invented certain new and useful Improvements in Whip-Sockets; and I do hereby declare the following to be a full, clear, and exact description of the invention, such as will enable others skilled in the art to which it appertains to make and use the same.

This invention relates to whip sockets and the object is to provide an improved form of socket wherein the whip will be securely held against malicious or felonious abstraction.

Another object of the invention is to provide an improved form of socket arranged to hold the whip handle from rattling therein but which may be readily released to permit the withdrawal of the whip.

A still further object of the invention is to provide a means whereby the locking device may be held in either closed or open position.

With the above and other objects in view as will hereinafter become apparent, the invention consists in general of a whip socket, a whip clamp arranged to be projected within or withdrawn from said whip socket, locking means for said clamp, and other means, to hold said clamp in open or closed position.

The invention further consists in certain novel details of arrangement and combinations of parts to be hereinafter fully described, illustrated in the accompanying drawings, and specifically set forth in the claims.

In the accompanying drawings, like characters of reference indicate like parts in the several views, and:—Figure 1 is a front elevation of a whip socket constructed in accordance with this invention. Fig. 2 is a longitudinal transverse section of such a socket showing the clamp in closed position. Fig. 3 is a similar view showing the clamp in open position.

The numeral 10 indicates the body of the socket. This body is provided with a slot 11 in one side thereof and upon the opposite side from the slot are provided suitable fastening means not being necessary here to be shown as they form no part of the invention. On either side of the slot 11 and at the upper end thereof is located an ear 12

provided with a suitable bend to receive a pin 13. This ear is so arranged that it projects a considerable distance beyond the body of the socket as clearly shown in Figs. 2 and 3. Mounted upon the pin 13 is a lever 14, the arms of which are bent at substantially right angles to each other. The shorter arm of this lever is arranged to project through the slot 11 when the device is in locking position and upon the face of this shorter arm is preferably provided a pad of some soft material such as rubber or the like as indicated at 15. The object of providing this face with this soft pad is to prevent damage to the handle of valuable whips. The outer side of the short arm is a plane surface as indicated at 16, and the longer arm has a similar plane surface 17 at right angles to the first mentioned plane surface 16 and forming with said surface the outer corner of the lever. Upon the lower portion of the lever is formed a flattened surface 18 adapted to contact with the body 10 of the whip socket so that the motion of the lever 14 inward when in the position shown in Fig. 2 is thereby limited. The extreme end of the longer arm of the lever is preferably provided with a finger-piece 19 so arranged that a person's fingers may be readily inserted below the same for the purpose of raising the lever to the position shown in Fig. 3. Between this finger-piece 19 and the pin 13 is formed an aperture 20. Upon the lower end of the whip socket is formed a pair of spaced ears 21 provided with apertures arranged to register with the apertures 20 as clearly indicated at 22.

In order to hold the lever in the position shown in Fig. 2 there is provided a lock 23 of any ordinary form and arranged so that the bow of the lock passes through the apertures 20 and 22 thus securely holding the lever 14 in locked position.

For the purpose of retaining the lever 14 in either the locked or unlocked position there is provided at the upper front portion of the socket a spring 25. The lower end of this spring is bent as indicated at 26. This bent portion is arranged to rest in one or the other of notches 27 formed in the flattened faces of the lever.

It is obvious that this device may be used in connection with any form or type of whip socket and it is further obvious that minor changes may be made in the form and the constructions of the parts thereof

without departing from the material principle involved. It is not therefore desired to confine the invention to the exact form herein shown and described, but it is wished 5 to include all such as properly come within the scope thereof.

Having thus described the invention, what is claimed as new, is:—

1. In a device of the kind described, a whip socket provided with a slot at one side thereof, a pivoted clamping member adapted to be projected through the slot, a pair of right-angled faces provided on said clamping member, a spring held on 15 said socket and arranged to press against said clamping faces accordingly as one or the other is positioned beneath said spring.
2. In a device of the kind described, a whip socket provided with a longitudinal slot at one side thereof, a bent lever pivoted adjacent the slot and having one arm arranged to project therein to clamp a whip, the other arm of said lever being provided with a lock-receiving aperture, a pair of 25 spaced ears formed on said socket each provided with an aperture adapted to register with the lock-receiving aperture of said clamping member, and a lock adapted to pass through said apertures and securely 30 lock said clamping member in position.
3. In a device of the kind described, a

whip socket provided with a slot at one side thereof, a pair of spaced ears formed adjacent said slot, said ears being provided with pin-receiving apertures, a pin held in said 30 apertures, a bent lever forming a clamping member pivoted on said pin, one arm of said lever being arranged to project within the socket and lock a whip or be withdrawn therefrom as the lever is rotated, the 40 other arm of said lever being provided with a lock-receiving aperture, a pair of spaced apertured ears upon the lower end of said socket arranged to have the apertures therein in alignment with the lock-receiving aperture of the clamping member when the same is in clamped position, a right-angled corner formed on said clamping member, a 45 spring held on said socket arranged to press against one or the other of the faces of said 50 right-angled corner as the same is brought into position beneath the spring, and a lock adapted to pass through the apertures in said ears and the arm of the clamping member and hold the same in locked position. 55

In testimony whereof, I affix my signature, in presence of two witnesses.

JOHN C. FEICKERT.
